BENJAMIN F. OLER, OF ELMHURST, NEW YORK, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,116,320.

Specification of Letters Patent.

Patented Nov. 3, 1914.

Application filed March 1, 1913. Serial No. 751,400.

To all whom it may concern:

Be it known that I, BENJAMIN F. OLER, a citizen of the United States, residing at Elmhurst, in the county of Queens and State of New York, have invented certain new and useful Improvements in Railway-Traffic-Controlling Apparatus, of which the following is a specification.

My invention relates to railway traffic controlling apparatus and particularly to apparatus for giving a signal aboard a moving car or train or for controlling the speed of a car or train.

I will describe one form and arrangement of apparatus embodying my invention and will then point out the novel features thereof in claims.

In the accompanying drawings, Figure 1 is a diagrammatic view showing one form 20 and arrangement of apparatus embodying my invention. Fig. 2 is a view showing in side elevation portions of the apparatus shown in Fig. 1.

Similar reference characters refer to similar parts in each of the several views.

Referring to the drawings, A, A designate the track rails of a railway, and B is a vehicle adapted to travel thereon. The vehicle B may for example be a locomotive car, 30 or train. This vehicle B is provided with a suitable governing means such for example as an air brake train pipe 14 in which is a valve V controlled by an electromagnet M. When the electromagnet M is energized it 35 holds the valve V closed and the brakes are therefore not applied, but when the electromagnet M is de-energized it allows valve V to open thereby causing an application of the air brakes. This arrangement of control 40 of air brakes is well understood in the art.

Mounted in the trackway are two magnetic cores 10 and 11; one of these cores 10 is a permanent magnet and is therefore constantly magnetized; the other core 11 is of 45 soft iron and is provided with a winding 15 by means of which it may at times be magnetized. This winding 15 is provided with a circuit which may be controlled in any suitable manner; as here shown it is controlled by a track relay R which is included in a track circuit C. This track circuit C comprises portions of the track rails A, A electrically separated from the adjoining portions by insulated joints 19, 19, a track 50 battery 20 and the relay R. The circuit for

winding 15 is from source of current 22 through armature contact 23 of relay R, wire 24, winding 15, wire 25, armature contact 26 of a relay 21, wire 27 to source 22. It will be seen therefore that when the track 60 relay R is open, core 11 is de-magnetized; and that when this track relay R is closed, core 11 will be magnetized provided the circuit for winding 15 is not open at some other point.

Mounted on the vehicle B are two magnetic cores 12 and 13, both of which are of soft iron. The cores 12 and 13 are arranged to register respectively with the trackway cores 10 and 11, and as illustrated in Fig. 2 70 the cores 12 and 13 are mounted so that they pass in close inductive relation with the cores 10 and 11 respectively as the vehicle proceeds along the trackway. The core 12 is provided with a winding 18, and the core 13 75 is provided with a winding 17. These windings are included in a circuit which includes a source of current 33 and a relay 34, the circuit being from source 33 through wire 35, relay 34, wire 36, armature contact 37 of 80 relay 34, wire 38, winding 17, wire 39, winding 18, wire 40 to source 33. The relay 34 controls the electromagnet M by means of the following circuit—from source of current 41 through wire 42, electromagnet M, 85 wire 43, contact 44, wire 45, to source 41.

It will be seen from the foregoing that normally the relay 34 is energized from the source 33 and is therefore closed, so that magnet M is energized and the air brake 90 valve V is therefore held closed. The circuit including relay 34 is however affected as the cores 12 and 13 pass over cores 10 and 11, in the manners which I will now explain.

I will first assume that the track relay R 95 is open due to the presence of a car or train in the track circuit C or to some other cause, so that the circuit of winding 15 is open and the core 11 is therefore de-magnetized. As the vehicle B approaches the track circuit C, 100 the cores 12 and 13 pass over the cores 10 and 11, and as the former cores approach the point at which they are exactly superposed upon the latter cores, the magnetized core 10 induces magnetic flux in core 12, which flux 105 in turn induces a momentary voltage in winding 18. Core 13 is magnetized hence as this core approaches core 11, a voltage is induced in winding 17. The voltages thus induced in the circuit of relay 34 are in the 110

2

same direction and their sum is equal and opposite to the voltage of battery 33, so relay 34 opens, thereby deenergizing magnet M and applying the brakes. Since the circuit for relay 34 includes an armature contact 37 of the relay, it will be seen that when the relay 34 is once opened it will remain open until closed by some auxiliary means. The means which I have here shown 5 comprises a branch around contact 37, which branch includes a circuit controller 46 which is normally open but can be closed by hand when necessary. This circuit controller 46 is preferably sealed, so that when it has 10 been closed the fact will be indicated by the breakage of the seal.

I will now assume that the track relay R is closed, and that the circuit of winding 15 is closed at all other points also, so that core 20 11 is magnetized. Under these conditions, as the cores 12 and 13 approach the point at which they are exactly superposed upon cores 10 and 11, magnetic flux will be induced in both of the cores 12 and 13 and the 25 momentary voltages induced in the relay circuit are equal and opposite in direction so that they neutralize each other and therefore have no effect on the current flowing in the circuit due to battery 33. Hence relay 34 remains closed and the brakes are not applied.

I have found that the magnetism of a permanent magnet will sometimes decrease or disappear entirely. To avoid either of these conditions, I prefer to provide the permanent magnet 10 with a winding 16 by 35 means of which the magnetism of this magnet may be maintained. This winding 16 is provided with a circuit which includes a source of current and a detecting means for 40 indicating a cessation of current in the circuit; as here shown the circuit comprises a source of current 47, the winding 16 and a relay 21 all connected in series. As hereinbefore pointed out, the circuit for winding 45 15 includes contact 26 of relay 21, hence it will be seen that if the circuit for winding 16 becomes open or if the current in this circuit is reduced below a predetermined point, so that relay 21 opens, the circuit for winding 50 15 is opened and the vehicle B will be brought to a stop when it passes over the cores 10, 11.

By making the core 10 a permanent magnet, and providing a normally energized 55 winding 16 on this core to maintain the magnetism therein, and a detecting device to indicate cessation of current in the winding, I have eliminated practically all possibility of an undetected failure of magnetism in the 60 core for the following reasons: Under normal conditions the core is magnetized both because of its own permanent magnetism and because of the flux induced by winding 16. If the current in winding 16 should 65 fail, an indication of this fact would be

given but the magnet 10 would retain its magnetism long enough to stop the vehicle.

I have in the drawing shown a signal S governing traffic through the track circuit C. As here shown this signal is controlled both 70 by the track relay R and by the detector relay 21, the circuit for the signal being from the source 22 through contact 28, wire 29, contact 30, wire 31, signal S, wire 32 to the source 22. With this arrangement of control 75 it will be seen that if the current in winding 16 fails, signal S will indicate "stop". This control of the signal by relay 21 may however be omitted if desired, and in fact the signal itself is not essential 80 and forms no part of my invention.

Although I have herein shown and described only one form of traffic controlling apparatus embodying my invention, it is understood that various changes and modifications may be made therein within the scope of the appended claims without departing from the spirit and scope of my invention.

Having thus described my invention, what 90 I claim is:—

1. In combination with the trackway of a railway and a vehicle traveling thereon, two magnetic cores located in the trackway one of which cores is constantly magnetized, 95 means for magnetizing and de-magnetizing the other core, means on the vehicle for governing said vehicle, a normally closed electric circuit on the vehicle including a source of current, a magnet included in said circuit for controlling the said governing means, two magnetic cores carried on the vehicle and arranged to register respectively with the two said cores in the trackway, a winding on each of the said vehicle-carried cores, said windings being included in the said electric circuit and so connected in said circuit that when both trackway cores are magnetized the voltages induced in the circuit when the vehicle cores pass over the 100 trackway cores are in opposite directions and are substantially equal.

2. In combination with the trackway of a railway and a vehicle traveling thereon, two magnetic cores located in the trackway one 115 of which cores is constantly magnetized, means for magnetizing and de-magnetizing the other core, means on the vehicle for governing said vehicle, a normally closed electric circuit on the vehicle including a source 120 of current, a magnet included in said circuit for controlling the said governing means, two magnetic cores carried on the vehicle and arranged to register respectively with the two said cores in the trackway, a winding on each of the said vehicle-carried cores said windings being included in the said electric circuit and so connected therein that when the vehicle-carried cores pass over the 125 trackway cores, if the second-mentioned 130

trackway core is de-magnetized the voltages induced in the windings of the vehicle cores will counteract the voltage in said circuit due to the said source and thereby de-magnetize the said magnet, but if the second-mentioned trackway core is magnetized the voltages induced in the windings of the vehicle cores will neutralize each other and will therefore not affect the current from the 10 source in said circuit.

3. In combination with the trackway of a railway and a vehicle traveling thereon, two magnetic cores located in the trackway one of which cores is a permanent magnet, and 15 the other a soft iron core, means for magnetizing and de-magnetizing the soft iron core, means on the vehicle for governing said vehicle, a normally closed electric circuit on the vehicle including a source of current, 20 a magnet included in said circuit for controlling the said governing means, two magnetic cores carried on the vehicle and arranged to register respectively with the two said cores in the trackway, a winding on 25 each vehicle-carried core said windings being included in said electric circuit and so connected therein that the voltages induced in the windings when the soft iron core is not magnetized will neutralize the voltage of the 30 said source but that the voltages induced in said windings when the soft iron core is magnetized will neutralize each other thereby having no effect on the current from said source.

35 4. In combination with the trackway of a railway and a vehicle traveling thereon, two magnetic cores located in the trackway, one of which cores is a permanent magnet, and the other a soft iron core provided with an 40 energizing winding, a track circuit including a track relay, a circuit for said energizing winding including a source of current which circuit is controlled by a front contact of the track relay, means on the vehicle 45 for governing said vehicle, a normally closed electric circuit on the vehicle including a source of current and a magnet for controlling the said governing means, two magnetic cores carried by the vehicle and arranged to 50 register respectively with the two said cores in the trackway, a winding on each vehicle-carried core said windings being included in said vehicle circuit and so connected therein that the voltages induced in the windings 55 when the soft iron core is demagnetized will neutralize the effect of the source of current in the vehicle circuit but that the voltages induced in said windings when the soft iron is magnetized will neutralize each other 60 thereby having no effect on the current in the vehicle circuit.

5. In combination with the trackway of a railway and a vehicle traveling thereon, two magnetic cores located in the trackway one of which cores is a permanent magnet, and

the other a soft iron core, an energizing coil on the permanent magnet for maintaining the magnetism therein, a circuit for said coil including a source of current and a relay, a coil on the other core and a circuit therefor controlled by said relay, other means for also controlling the last-mentioned circuit, means on the vehicle for governing said vehicle, a normally closed electric circuit on the vehicle including a source of current and means for controlling said governing means, two magnetic cores carried on the vehicle and mounted to register respectively with the two said cores in the trackway, a winding on each vehicle carried core, said windings being included in said vehicle circuit and so connected therein that the voltages induced in said windings when the soft iron core is de-magnetized will neutralize the voltage in the vehicle circuit but that the voltages induced in said windings when the soft iron core is magnetized will neutralize each other and will therefore have no effect on the current in the vehicle circuit.

6. In combination with the trackway of a railway and a vehicle traveling thereon, a permanent magnet located in the trackway, a winding carried by the vehicle and mounted to pass in inductive relation to said magnet, means on the vehicle controlled by the voltage induced in said winding by said magnet, a coil on said magnet for maintaining the magnetism of the magnet, a circuit for said coil including a source of current, and means controlled by said circuit for indicating the cessation of the current in the circuit.

7. In combination with the trackway of a railway and a vehicle traveling thereon, a permanent magnet located in the trackway, a winding carried by the vehicle and mounted to pass in inductive relation to said magnet, means on the vehicle controlled by the voltage induced in said winding by said magnet, a coil on said magnet for maintaining the magnetism of the magnet, a circuit for said coil including a source of current, a relay controlled by said circuit, a railway signal, and a circuit for said signal controlled by said relay.

8. In combination with the trackway of a railway and a vehicle traveling thereon, a permanent magnet on one of said members, a winding on the other member mounted to pass in inductive relation to the said magnet, means controlled by the voltage induced in said winding by the magnet, a coil on said magnet for maintaining the magnetism of the magnet, a circuit including said coil and a source of current, and means controlled by said circuit for indicating the cessation of current in the circuit.

9. In combination, a permanent magnet, railway traffic controlling apparatus controlled by said magnet, a coil on said mag-

net for maintaining the magnetism of said magnet, a circuit for said coil including a source of current, and means controlled by said circuit for indicating a cessation of current in the circuit.

5 10. An inductive device comprising a winding and a permanent magnet, means for moving one of said members relatively to the other to induce voltage in the winding, 10 railway traffic controlling apparatus controlled by voltage induced in said winding by the magnet, a coil on the magnet for

maintaining the magnetism of said magnet, a circuit including said coil and a source of current, and means controlled by said circuit for indicating a cessation of current in the circuit. 15

In testimony whereof I affix my signature in presence of two witnesses.
